US00D776612S

(12) **United States Design Patent** (10) **Patent No.:** **US D776,612 S**
Chen et al. (45) **Date of Patent:** **** Jan. 17, 2017**

(54) **CHARGEABLE BATTERY**

(71) Applicant: **SZ DJI TECHNOLOGY CO., LTD.**,
Shenzhen, Guangdong (CN)

(72) Inventors: **Shaojie Chen**, Shenzhen (CN); **Yin Tang**, Shenzhen (CN)

(73) Assignee: **SZ DJI TECHNOLOGY CO., LTD.**,
Shenzhen (CN)

(**) Term: **14 Years**

(21) Appl. No.: **29/513,072**

(22) Filed: **Dec. 26, 2014**

(30) **Foreign Application Priority Data**

Jul. 1, 2014 (CN) 2014 3 0216200

(51) **LOC (10) Cl.** **13-02**

(52) **U.S. Cl.**

USPC **D13/103**

(57) **CLAIM**

The ornamental design for a chargeable battery, as shown and described.

DESCRIPTION

FIG. 1 is a perspective view of a chargeable battery showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken lines are for illustrative purposes only and form no part of the claimed design.
